Henry Hunt of Abington, Mass.

DES. 2067

Letters Patent No. 2067 Dated May 16-1865.

Design for a Shoe.

The schedule referred to in these letters Patent and making part of the same.

To all whom it may concern:

Be it known that of Henry Hunt, of Abington, in the County of Plymouth and State of Massachusetts, have originated and produced a new and ornamental design or configuration for a shoe, of which the following is a full and clear description, reference being had to the accompanying drawings, making part of this specification.

The object of this design is the ornamentation of the outer surface of the soles of a shoe by giving to it a checkered or blocked appearance, as seen in the drawing, the square, rectangular or lozenge shaped figures being produced by pressure of dies or any other suitable mechanism, the invention in no way relating to these alone, but consisting only in such an ornamentation without regard to the method by which it is produced.

I claim The ornamental design for a shoe, as shown and described.

In witness whereof I have hereunto set my hand this fourteenth day of April A.D. 1865.
